UNITED STATES PATENT OFFICE.

HYRUM SPILLMAN, OF POCATELLO, IDAHO.

GRATE.

1,408,481.

Specification of Letters Patent. Patented Mar. 7, 1922.

Application filed September 5, 1919. Serial No. 321,809.

To all whom it may concern:

Be it known that I, HYRUM SPILLMAN, a citizen of the United States, residing at Pocatello, in the county of Bannock and State 5 of Idaho, have invented a new and useful Grate, of which the following is a specification.

This invention relates to improvements in stoves and furnaces, and more particularly 10 to the grate construction thereof.

The object of the invention is to provide a grate construction wherein the weight of the firebed supported thereby is equally proportioned throughout the stationary and 15 rotary members thereof.

A further object of the invention is to provide a grate wherein the firebed supporting surface of the grate bar may be changed at intervals, thereby increasing the life of 20 the grate.

A still further object of the invention is to provide a rotary grate construction possessing equally as efficient shaking qualities as the horizontally reciprocating grates 25 now in use, and one which will not accidentally dump the grate during the shaking operation.

With the foregoing and other objects in view which will appear as the description 30 proceeds, the invention resides in the combination and arrangement of parts and in the details of construction hereinafter described and claimed, it being understood that changes in the precise embodiment of 35 the invention herein disclosed, may be made within the scope of what is claimed, without departing from the spirit of the invention.

Referring to the drawing:

Figure 1 illustrates a top plan view of a 40 grate and its support, constructed in accordance with the present invention.

Figure 2 illustrates a side elevational view of the same.

Figure 3 illustrates an end elevational 45 view of the grate; and

Figure 4 illustrates a fragmentary section of the grate and its support.

Referring to the drawing in detail, the reference character 5 designates the support 50 for the grate, which is shown as preferably rectangular in form, but it is to be understood that the size and form of the frame may be varied to meet various requirements without departing from the 55 spirit of the invention.

This supporting frame is of a size to fit within the usual firebox of a stove or furnace, and includes the end members 6 and 7 which support the bracket members 8 bolted thereto as at 9, the same being provided with central openings constituting bearings by means of which the ends of the shaft 11 of the grate bar is supported. The main grate includes the grate frame 12 which is constructed to support the disks 13, the 60 disks 13 being secured to the frame by means of the securing members 15. The disks 13 are also provided with central openings to accommodate the shaft 11 which forms a part of the grate bar. This grate bar has the 65 disks 14 supported thereon and disposed in spaced relation throughout the length of the shaft 11, the disks 14 being shown as disposed between adjacent disks 13, the disks 14 being of diameters less than the distance 70 between the side members of the frame 12 to permit the same to rotate freely therebetween.

The frame 12 is preferably formed of upper and lower sections 16 and 17, each section having the front and rear heads 18 and 19, the front heads 18 being provided with extensions 20 which are disposed within the central opening of the forward bracket 8. 80

The forward ends of the extensions 20 85 are provided with cut out portions 21 forming clutch faces 22 to receive the correspondingly formed clutch faces formed on the operating handle 23, said operating handle being provided with a central opening 90 adjacent the clutch faces which opening is squared to correspond with the squared extremity 24 of the operating shaft 11.

From the foregoing it will be seen that if it becomes necessary to move the grate 95 bar to accomplish the shaking thereof, the operating handle 23 which is formed with a squared opening is positioned on the squared extremity 24 of the shaft 11, the handle is then given slight movements to the 100 right and left, resulting in the partial rotary movements of the disks 14 with relation to the disks 13.

If it becomes necessary to dump the fire, the handle is positioned as before stated, 105 and forced forwardly on the shaft until the clutch faces thereof engage the clutch faces 22 of the extension 20, locking the handle to the extension. The handle is given a complete turn with the result that the coals 110

of the fire fall between the disks 13 and 14 and the side members of the frame.

In the event that it is desired to reverse the supporting surface of the grate bar, the handle is positioned on the squared extremity 24 of the shaft 11 and given a turn. The handle is now forced inwardly until the clutch faces are brought into engagement, whereupon a turn of the handle results in the main grate member being rotated to bring the reverse side thereof in an upper position.

Having thus described the invention, what is claimed as new is:—

15 In a grate construction, a supporting frame, a main grate member including a frame, disks supported by the frame, a grate bar including a shaft, said shaft having a squared end, disks supported on the shaft

and disposed between the disks of the main 20 grate member, said main grate member including heads having extensions provided with clutch faces in combination with an operating handle having a clutch face, said operating handle having a squared opening 25 to accommodate the squared end of the shaft to rotate the grate bar and being adapted to be moved to bring the clutch faces in mesh with the clutch faces of the main grate member to rotate the same, and 30 bearings for supporting the grate bar.

In testimony that I claim the foregoing as my own, I have hereto affixed my signature in the presence of two witnesses.

HYRUM SPILLMAN.
